UNITED STATES PATENT OFFICE.

ROBERT JARVIS SMOTHERS, OF HOLYOKE, MASSACHUSETTS, ASSIGNOR TO JAMES T. ROBINSON, OF HOLYOKE, MASSACHUSETTS.

CIRCUIT OPENING AND CLOSING DEVICE.

Application filed September 11, 1925. Serial No. 55,807.

This invention relates to a circuit opening and closing device designed primarily for use for lighting circuits employed with photographic printing machines of the step and repeat type, more particularly to the type of step and repeat photographic printing machine as disclosed in my application to-wit:—filed Nov. 7, 1925, Serial Number 67,596, but it is to be understood that a circuit opening and closing device, in accordance with this invention, can be employed for use in any connection for which it is found applicable, and the invention has for its object to provide, in a manner as herein-after set forth, a device of the class referred to for regulating the duration period for the closing of a circuit to control the service application of the current, whereby when the device is employed with a lighting circuit for photographic printing, in accordance with the step and repeat method, the period necessary for the application of light rays to a particular photographic plate will be obtained to ensure clear, accurate, uniform, distinct and perfect photographic prints from the plate upon a sensitized surface.

Further objects of the invention are to provide, in a manner as hereinafter set forth, a circuit opening and closing device which is simple in its construction and arrangement, strong, durable, compact, thoroughly efficient in its use for the purpose intended, readily installed, and comparatively inexpensive to manufacture.

With the foregoing and other objects in view, the invention consists of a novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views—

Figure 1 is an elevation of a circuit opening and closing device, in accordance with this invention, showing the adaptation thereof in connection with a lighting circuit.

Figure 2 is a section on line 2—2, Figure 3.

Figure 3 is a section on line 3—3, Figure 1.

Figure 4 is a section on line 4—4, Figure 3.

Figure 5 is a section on line 5—5, Figure 3.

Figure 6 is a section on line 6—6, Figure 2.

A circuit opening and closing device, in accordance with this invention, includes a pivoted latch 1, to be hereinafter referred to, which releasably retains the device in position to open the circuit with which the device is employed, and as shown, by way of example, the device is employed in connection with a lighting circuit for the lamp 2. The latch 1 is shifted to released position to permit of the operation of the device to close the circuit for a predetermined period to control the service application of the current, or to control the illumination of the lamp 2. When the device operates in a direction to open the circuit, it is again engaged by the latch 1 and held in such position until the latch is again shifted to release the device so it can operate to close the circuit for a predetermined period. The adaptation of a circuit opening and closing device, in accordance with this invention, is shown in connection with a lighting circuit employed for photographic printing and the latch 1 is shifted to released position by a shifting member therefor carried by a movable part of a photographic printing machine, such movable part being an element of a lamp house shifting means and such element is indicated at 3. The element 3 has secured thereto, so as to bodily move therewith, a tubular member 4 which has extending therethrough and threadably engaging with the inner face thereof the shifting member 5 for the latch 1. The member 5 is bodily carried with the member 4 and element 3 during the shifting of the latter. The element 3 may move in a vertical or inclined position. It is to be understood that any suitable means can be employed for shifting the member 5 to actuate the latch 1, but with the member 5 preferably adjustably connected to the means which shifts or moves it. The member 5 is arranged over the latch and consists of a substantially elongated cylindrical bar threaded on its lower portion and provided with a head 6

90

95

100

105

having a knurled edge to facilitate the adjusting of the member 5 relative to the latch 1.

The circuit opening and closing device 5 comprises a stationary casing or housing consisting of a body portion formed of two sections, one of which is indicated generally by the reference character 7 and the other of which generally by the reference character 8. The section 7 is channel-shaped in plan and forms a side wall 9, a front wall 10 and a rear wall 11 of the housing. The section 8 is channel-shaped in vertical section and forms the other side wall 12, the top wall 13 and the bottom wall 14 of the housing. Secured to the inner face of the rear wall 11 and flush with the top and bottom edges of said wall are supporting pieces 15, 16 respectively and each of which 15 extends from the inner face of the side wall 9 and terminates at a point inwardly with respect to the side edge of the wall 11. Secured to the inner face of the rear wall 11 and abutting against the supporting pieces 15 and 16, is a vertically disposed bar 17 which also forms a supporting piece. The holdfast devices for securing the supporting pieces to the inner face of the wall 11 are indicated at 18. The bar or supporting piece 17 is flush with the vertical edge of the wall 11. The supporting piece 15 is formed intermediate its ends with an opening 19 having a threaded wall. The supporting piece 16 is provided intermediate its ends 35 with an opening 20 having a threaded wall, and the bar or supporting piece 17 is provided intermediate its ends with a pair of spaced openings 21 having threaded walls. Secured to the inner face of the front wall 10 at the top thereof, as well as being flush with the upper edge of said wall, is a supporting piece 21' which extends from the side wall 9 and terminates at a point removed from the vertical edge of the wall 10 and holdfast devices 22 are employed for securing the supporting piece 21' to the wall 10. The supporting piece 21' intermediate its ends is formed with an opening 23 having a threaded wall. Secured to the inner face of the wall 10, by the holdfast devices 24 is a supporting piece 25, which is flush with the lower edge of the wall 10 and has its inner ends spaced from the inner face of the side wall 9 and its outer end spaced from the vertical edge of the wall 10. The supporting piece 25 is formed with an opening 26 having a threaded wall. Secured to the inner face of the wall 10 and flush with the vertical edge thereof, as well as abutting against the outer ends of the supporting pieces 21 and 25 is a vertically disposed bar 27, which also forms a supporting piece and said bar 27 is provided intermediate its ends with a pair of spaced openings 28 having threaded walls.

The holdfast devices for securing the bar 27 of the wall 10 are indicated at 29.

When the sections 7 and 8 are arranged in co-active relation to provide the housing, the section 8 overlaps the top and bottom edges of the walls 10 and 11, seats against the supporting pieces 15, 16, 21' and 25, bears against the supporting pieces 17 and 27 and further abuts against the vertical edges of the walls 10 and 11. Section 8 is secured with the section 7 by holdfast devices 30, detachably engaging the walls of the openings 19, 20, 23, 26 and 27.

The side wall 9, intermediate its ends, is formed with a vertically disposed slot 31. The bottom wall 14 is formed with a lengthwise extending key-hole-shaped slot 32. The front wall 8 has extending therethrough, near the upper end thereof, a pair of flanged sleeves 33, only one of which is shown, for the passage of the encased circuit wires 34 and 35 into the chamber 36 formed by the housing. The circuit wires 34 and 35 extend from their covering as at 37, at the upper portion of the chamber 36, and project in opposite directions from the cover 37. The circuit wires 34, 35 when projected from the covering 37 have a portion of insulation thereof removed somewhat whereby the conductor will be of less diameter than with the insulation thereon. The front wall 10 is provided with a bracket 38 for anchoring the housing stationary to a suitable support. The support to which the bracket 38 is anchored is the body of the machine 100 with which the circuit opening and closing device is employed. The front wall 10 at its lower end is provided with a vertically disposed slot 39 through which extends an arm of the latch 1 so that such arm will be 105 in the path of the lower end of the shifting member 5 therefor. The shifting member 5 after being adjusted, is secured in adjusted position by the set screw 40.

Fixedly secured to the inner face of the side wall 9, as well as spaced therefrom, is a vertically disposed rectangular plate 40 of insulation, provided in its upper portion with a lengthwise extending slot 41, which opposes the slot 31. Positioned against that 115 face of the plate 40, which opposes the inner face of the wall 12, is a pair of spaced strips of insulation 42, 43 having their opposed side edges undercut as at 44. The plate 40, in connection with the strips 42, 43 form a 120 dove-tail groove 45 for a vertically movable carrier 46 formed of a rectangular plate of insulation and which has imbedded in its outer face a tapered contact member 47, of the same length as the length of the carrier 125 46 and which gradually increases in width from the bottom edge to the top edge of the carrier 46.

Secured to the upper end of the strips 42, 43 is a spacing block 48 of insulation. 130

Mounted on the block 48, as well as secured therewith and depending therefrom is a rectangular flat support 49 also formed of insulation material. Secured to the lower 5 ends of the strips 42, 43 and overlapping the carrier 46 are retaining pieces 50, 51 also formed of insulation and which also act as stops for an oscillatory circuit closing mechanism to be presently referred to.

10 The means for securing plate 45 to the wall 9 is indicated at 52. The means for securing the spacing pieces 48, support 49, strips 42 and 43 and plate 40 together is indicated at 53. The means for securing the 15 retaining pieces 50, 51, strips 42 and 43 and plate 40 together is indicated at 54. The strips 42 and 43 provide guides for the movement of the carrier 46. The strip 42 is also secured to the plate 40 by a securing 20 means 55. The securing means 53, 54 and 55 are in the form of holdfast devices consisting of short headed screws carrying nuts at one end, exteriorly of the plate 40 and opposing the wall 7. The securing means 25 52 is in the form of screws and which extends through the wall 9 and threadedly engages in the plate 40 at the upper portion thereof and which fixedly retains the plate 40 in position and when in position it abuts 30 against the inner face of the wall 10. The plate 10 is suspended slightly above the bottom wall 14 and is spaced from the walls 8, 11 and 13. The height and width of the plate is materially less than the height and 35 width of the housing.

The carrier 46, substantially centrally thereof, is provided with a countersunk opening 56, in which is mounted the head 57 of a manually shiftable bolt 58. The head 40 57 is spaced from the contact member 47, as well as insulated therefrom as at 59, that is to say, if the element 58 is formed of conducting material, if not, the insulation 59 is not necessary. The elements 57 extend outwardly through the slot 41, the plate 40 and slot 31 in the wall 9 and has a threaded outer end with which engages a clamping nut 60, suitably insulated and said nut 60 bears against a washer 61 carried by the 50 element 58 and which acts as a means in connection with the nut 60 and element 58 for fixedly maintaining the carrier 46 in the position to which it has been adjusted.

55 The circuit conductor or wire 35, is electrically connected with the contact member 47, as at 62. The circuit conductor or wire 34 is electrically connected, as at 63 to a conducting arm 64, which is secured at one end to the upper portion of the member 49 and has its other end bent inwardly or inturned 60 upon itself as at 65 for the purpose of forming a contact abutment.

Secured to the support 49 below the arm 64 is a pair of spaced stop pins 66, 67. 65 Pivotally connected to the member 49, as

at 68, and below the pins 66, 67, is an oscillatory conductor member which normally contacts with the abutment formed by the inturned end of the arm 64 and said conductor member is formed of a yoke-shaped 70 lower portion 69 having an upwardly extending arm 70 formed integral therewith. The arm 70 extends between the pins 66, 67 and below the inner face of the arm 64. The lower portion 69 is of inverted yoke- 75 shape and depends below the member 49. The yoke-shaped lower portion 69 of the conductor member has its arms arranged in the path of the circuit opening and closing element of a spring controlled oscillatory circuit opening and closing mechanism which is arranged below the supporting member 49 and is engaged by the latch 1 for the purpose of releasably retaining 80 said mechanism in a position when the circuit is open. The said oscillatory circuit opening and closing mechanism not only contacts with the conductor member but also with the contact member 47.

85 The oscillatory circuit opening and closing mechanism is shifted to close the circuit through the medium of a controlling spring therefor and returned to inactive position, or positioned to open the circuit, also by a controlling spring. The controlling spring 90 will be presently referred to. The oscillatory circuit opening and closing mechanism also includes a governor to provide for its operation at uniform speeds when released to close the circuit and shifted to inactive 95 position to open the circuit.

100 The spring controlled oscillatory circuit opening and closing mechanism includes a headed pivot 71 which is fixedly secured as at 72 in the head 73 of a coupling member 74 105 which is secured to the plate 40. The head 73 of the coupling member 74 abuts against that face of the plate 40 which opposes the wall 12. The coupling member 74 is positioned near the lower end of the plate 40 and substantially at the vertical median thereof. Mounted on the pivot member 71 is a bell crank lever 75 formed of an upstanding arm 76 and a horizontally disposed arm 77 and with the latter of less length than the former. The arm 77 projects towards the latch 1 and the arm 76 extends toward the contact member 47. Positioned against each face of the arm 76 is a strip of insulation 110 and which are indicated at 78, 79. Mounted against the strip 78 is a holding plate 80 and arranged against the strip 79 is a wiper arm 81 which forms the circuit opening and closing element of said mechanism and is constructed of a length of conducting material bent to provide a portion 82 arranged over the upper end of the arm 76, a portion 83 positioned in close proximity to the supporting member 49 and a bow-shaped upper 115 terminal portion 84 adapted on the opera- 120

125

tion of the oscillatory mechanism to wipe the contact member 47 transversely thereof for the purpose of closing the circuit, for a predetermined period to control the service application of the current, or in other words to control the duration period for the activity of the light rays from the lamp 2 to provide for photographic printing. That part of the wiper arm 81, which projects above the arm 76 of the bell crank lever 75 is resilient and is so constructed as to be permanently maintained in abutting relation with respect to the supporting member 46, so that when the arm 81 is oscillated, it will engage the contact member 47, as the outer face of the latter is flush with the outer face of the member 46.

Positioned against that part of the arm 81, which is arranged against the strip 79, is a short tapered bar 85, of insulation, which projects above the upper end of the arm 76 of the bell crank lever 75, as well as above the portion 82 of the arm 81, and further is arranged in parallelism with respect to the portion 83 of the arm 81. The arms of the yoke-shaped lower portion 60 of the oscillatory conductor member are arranged in the path of the bar 85, when the latter moves in either direction. The bar 85, arm 81, strips 78, 79, and arms 76 of the bell crank lever 75 are secured together by the holdfast devices 86 and by this construction, when the bell crank lever 75 is shifted, the several elements connected to the arm 76 thereof will bodily move therewith. Electrically connected, as at 87 to the arm 70 of the oscillatory conductor member, is an electrically conductor 88, which is electrically connected, as at 89, to the oscillatory wiper arm 81 and by this arrangement when the wiper arm 81 is in engagement with the contact member 47, the travel of the current will be circuit wire 35, contact member 47, wiper arm 82, conductor 88, arm 70 of the oscillatory conductor member, conductor arm 64, and circuit connection 34. The circuit wires, which are encased in a single covering, lead from a suitable source of electrical energy to the lamp 2 and said circuit wires have interposed therein, as well as electrically connected therewith, the circuit opening and closing device, in accordance with this invention. That portion of the encased circuit wires leading from the source of electrical energy is indicated at 90, and the portion leading from the housing to the lamp 2 is indicated at 91.

Secured to the lower face of the arm 77, of the bell crank 75, by the holdfast devices 92, is a plate 93 provided at its inner end with a depending nose 94, and at its outer end with an arcuate arm 95 having its upper end formed with a seat 96 which is engaged by the latch 1 for the purpose of releasably locking the oscillatory mechanism in posi-

tion to maintain the circuit open. Fixedly secured to the holdfast device 54, is the upper end of a controlling spring 97, which has its lower end connected to the arm 77, as at 98. The oscillatory mechanism is maintained in position to provide an open circuit against the pulling action of the spring 97, see Figure 2. Mounted on the pivot member 71, as well as secured to the outer face of the arm 77, of the bell crank lever 75, is the hub 99 of a toothed quadrant which forms a part of the governor for the oscillatory mechanism. The hub 99 is secured to the arm 77 by the holdfast devices 92. Secured to the lower portion of the plate 40, at one side of the pivot member 71, and extending towards the wall 8, is a supporting bracket 101 carrying a shaft 102, provided with a pinion 103 which meshes with the teeth of the quadrant 100. Fixed to the shaft 102 is a pair of oppositely extending arms 104, each having its outer end weighted as at 105. The nose 94 contacts with a two-armed setting lever for restoring the oscillatory mechanism to normal position, which is circuit opening position. The setting lever is arranged below the bracket 101 and is indicated at 106. The arms of the lever 106 are designated at 107, 108 and the former is of greater length, as well as being arranged above the latter. A pivot member 109 is carried by the plate 40 and upon which is mounted one end of the lever 106. The nose 94 is positioned in the path of the arm 107 of the lever 106 and a controlling spring 110 is positioned in the path of the arm 108 of the lever 106. The spring 110 extends up through the slot 32 into the lower portion of the chamber 36 formed by the housing, and said slot 32 provides a clearance for the operation of the lever 106 when it is moved downwardly when the arm 77 of the bell crank lever 75 is moved upwardly by the action of the spring 97, and when said arm 77 moves in such direction, the nose 94 engaging the arm 107 will move the lever 106 downwardly against the action of the spring 110 and the force of the spring 110, after the spring 97 has contracted, will move the lever 106 upwardly and as the arm 107 engages the nose 94 the arm 77 will be moved in an opposite direction against the action of the spring 97, but by the time the spring 97 is in position to overcome the action of the spring 110, the latch 1 will engage the seat 96 and hold the parts of the oscillatory mechanism in the position shown in Figure 2. The spring 97 provides means for moving the arm 76 of the bell crank lever in a direction towards and over the contact member 47 and the spring 110 acts as a means for moving the bell crank lever 75 in an opposite direction, under such conditions an oscillatory movement is given to the

wiper member 81. When the arm 76 of the bell crank lever moves in a clockwise direction the governor mechanism operates in the same direction and when the arm 76 of the bell crank lever moves in a counter-clockwise direction the governor operates in a like direction and under such conditions the speed of the shift is controlled and uniform in either direction.

10 The spring 110 extends below the housing and is adjustably secured as at 111 to a stationary support 112, which may be the body of the machine with which the device is employed.

15 The latch which is referred to generally by the reference character 1, is spring controlled and consists of an up-standing hook-shaped arm 113 and a horizontally disposed arm 114 which extends through the slot 39 and in the path of the element 5. The pivot for the latch 1 is indicated at 115 and is carried by the plate 40. The controlling spring for the latch 1 is indicated at 116 and is arranged between the latch and the plate 40. One end of the spring 116 is connected to the plate 40 as at 117 and the other end to the latch 1, as at 118. The function of the controlling spring 116 is to maintain the latch 1 in the position shown in Figure 2, so that the bill of the arm 113 will be arranged in the path of the arcuate arm 95 so the bill can engage the seat 96 and be maintained in engagement therewith, by the spring 116.

20 For the purpose of controlling the service application of the current the carrier 46 is vertically adjusted so that any selected portion of varying width of the contact member 47 can be engaged by the bow-shaped end 44 of the wiper arm 81. If the bow-shaped end 84 of the wiper arm 81 moves over a narrow portion of the contact member 47, the duration period for the service application of the current would be less than if the bow-shaped end 84 moved over a wider part or portion of the contact member 47. By this arrangement, when the device is employed in connection with the lighting circuit for photographic printing, the exposure 25 of the printing plate to the light rays can be had in predetermined periods, that is a short or long exposure, due to which portion of the contact plate 47 is engaged by the wiper element.

30 The inturned portion 65 of the contact arm 64 is engaged by the arm 70 of the conductor member to close the circuit and said arm 64 has the major portion of its length offset with respect to that portion which 35 is secured against the plate 49 by the securing means 63. Therefore, when the arm 70 of the conductor member moves towards the pins 66 the circuit will be open. The pin 67 limits the movement in a clockwise direction of the arm 70 of the conductor member

so that said arm will engage the inturned portion 65.

The bar 85 acts as a means to oscillate the conductor member so that the arm 70 thereof will be moved into and out of engagement with the inturned portion 65 of the arm 64 and as before stated the inturned portion 65 constitutes an abutment contact. Normally the arm 70 of the conductor member is in engagement with the abutment contact 75 and which is caused by the bar 85 engaging the arm 69' of the conductor so that it will be rocked to the position shown in Figure 2. When the bar 85 moves in a clockwise direction, that is to say, away from the arm 80 69', the wiper member will engage with the contact member 47 and the circuit will be maintained closed as long as the wiper member is in engagement with the contact member 47. As the wiper member moves with the bar 85 in a clockwise direction, said bar 85 will engage the arm 69'' of the conductor member and shift the arm 70 of the conductor member out of contact with the inturned end 65 of the member 64. When the bar 85 engages the arm 69' the conductor member will be shifted to a position opposite to that shown in Figure 2 and the arm 70 thereof will engage the pin 66. At this time the bar 85 will be moved in a counter-clockwise direction and towards the arm 69', and during such movement of the bar 85 the wiper member will engage the contact 85 47, but as the arm 70 is out of engagement with the inturned portion 65 of the arm 64 90 the circuit will not be closed. As the bar 85 moves towards the arm 69', it will abut the latter, and at the time of abutment the latch 1 will engage the seat 96 and maintain the parts in the position as shown in Figure 95 2.

It is thought that the many advantages of a circuit opening and closing device, in accordance with this invention, and for the purpose set forth, can be readily understood, and although the preferred embodiment of the invention is as illustrated and described yet it is to be understood that changes in the details of construction can be had which will fall within the scope of the claims 100 hereunto appended.

What I claim is:

1. A circuit opening and closing device comprising an upper and a lower oscillatory element, and an adjustable contact wiped in opposite directions by said lower element and providing means for varying the duration period for the closing of a circuit to control the service application of the current, said upper element engaged by and oscillated on the operation of said lower element and coacting with the latter to close the circuit when said lower element moves in a clockwise direction to wipe said contact 110 and to provide for the opening of the circuit 115 120 125 130 135

when said lower element moves in an anti-clockwise direction to wipe said contact.

2. A circuit opening and closing device comprising an upper and a lower oscillatory element, and adjustable contact wiped in opposite directions by said lower element and providing means for varying the duration period for the closing of a circuit to control the service application of the current, 10 said upper element engaged by and oscillated on the operation of said lower element and coacting with the latter to close the circuit when said lower element moves in a clockwise direction to wipe said contact and 15 to provide for the opening of the circuit when said lower element moves in an anti-clockwise direction to wipe said contact, and means for oscillating said lower element.

3. A circuit opening and closing device 20 comprising an upper and a lower oscillatory element, an adjustable contact wiped in opposite directions by said lower element and providing means for varying the duration period for the closing of a circuit to 25 control the service application of the current, said upper element engaged by and oscillated on the operation of said lower element and coacting with the latter to close the circuit when said lower element moves 30 in a clockwise direction to wipe said contact and to provide for the opening of the circuit when said lower element moves in an anti-clockwise direction to wipe said contact, and means for oscillating said lower element, said means including a governor 35 for controlling the operation thereof.

4. A circuit opening and closing device comprising an upper and a lower oscillatory element an adjustable contact wiped 40 in opposite directions by said lower element and providing means for varying the duration period for the closing of a circuit to control the service application of the current, said upper element engaged by and oscillated on the operation of said lower element and coacting with the latter to close the circuit when said lower element moves in a clockwise direction to wipe said contact and to provide for the opening of the circuit when said lower element moves in 45 an anti-clockwise direction to wipe said contact, means for oscillating said lower element, and a latching element for releasably retaining said means from action when said lower element has been shifted to the limit of 50 its movement in an anti-clockwise direction.

5. A circuit opening and closing device comprising an upper and a lower oscillatory element, an adjustable contact wiped 60 in opposite directions by said lower element and providing means for varying the duration period for the closing of a circuit to control the service application of the current, said upper element engaged by and oscillated on the operation of said lower 65

element and coacting with the latter to close the circuit when said lower element moves in a clockwise direction to wipe said contact and to provide for the opening of the circuit when said lower element moves in an anti-clockwise direction to wipe said contact, means for oscillating said lower element, a latching element for releasably retaining said means from action when said lower element has been shifted to the limit of its 75 movement in an anti-clockwise direction, and means for shifting said latching element to release the means for oscillating said lower element.

6. A circuit opening and closing device 80 comprising an upper and a lower oscillatory element, an adjustable contact wiped in opposite directions by said lower element and providing means for varying the duration period for the closing of a circuit to 85 control the service application of the current, said upper element engaged by and oscillated on the operation of said lower element and coacting with the latter to close the circuit when said lower element moves 90 in a clockwise direction to wipe said contact and to provide for the opening of the circuit when said lower element moves in an anti-clockwise direction to wipe said contact, and a normally latched spring controlled 95 releasable means for oscillating said lower element.

7. A circuit opening and closing device comprising an upper and a lower oscillatory element, an adjustable contact wiped in opposite directions by said lower element and providing means for varying the duration period for the closing of a circuit to control the service application of the current, said upper element engaged by and oscillated on 100 the operation of said lower element and coacting with the latter to close the circuit when said lower element moves in a clockwise direction to wipe said contact and to provide for the opening of the circuit when 105 said lower element moves in an anti-clockwise direction to wipe said contact, and a normally latched spring controlled releasable means for oscillating said lower element, said means including a governor for 110 controlling the operation thereof.

8. A circuit opening and closing device comprising a normally stationary lengthwise adjustable contact for varying the duration period for the closing of a circuit to control 115 the service application of the current, means for bodily adjusting said contact lengthwise and to fixedly secure it in adjusted position to maintain a portion thereof in the path of a circuit closing means, a circuit closing 120 means travelling across said portion of said contact for closing the circuit for a predetermined period, and a normally latched spring controlled releasable means for operating said circuit closing means. 125 130

9. A circuit opening and closing device comprising a normally stationary lengthwise adjustable contact for varying the duration period for the closing of a circuit to control the service application of the current, means for bodily adjusting said contact lengthwise and to fixedly secure it in adjusted position to maintain a portion thereof in the path of a circuit closing element, an oscillating circuit closing element travelling across said portion of said contact for closing the circuit for a predetermined period when said element moves in one direction, operating means for said element, and means operated from said element to provide for the opening of the circuit when said element travels across the said portion in the opposite direction.
10. A circuit opening and closing device comprising means for varying the duration period for the closing of a circuit to control the service application of the current, an oscillatory circuit closing element travelling across said means for closing the circuit for a predetermined period when said element moves in one direction, means operated from said element to provide for the opening of the circuit when said element travels across said first mentioned means in the opposite direction, and a spring controlled releasable operating means for said element.
11. A circuit opening and closing device comprising a normally stationary lengthwise adjustable contact for varying the duration
- period for the closing of a circuit to control the service application of the current, a circuit closing means travelling across a portion of said contact for closing the circuit for a predetermined period, a normally latched spring controlled releasable means for operating said circuit closing means, said contact gradually decreasing in width from one end to the other and means for bodily adjusting said contact lengthwise and to fixedly secure it in adjusted position to maintain a portion thereof in the path of said circuit closing means.
12. A circuit opening and closing device comprising a normally stationary lengthwise adjustable contact for varying the duration period for the closing of a circuit to control the service application of the current, said contact gradually decreasing in width from one end to the other, means for bodily adjusting said contact lengthwise and to fixedly secure it in adjusted position to maintain a portion thereof in the path of a circuit closing means, a circuit closing means travelling across said portion for closing the circuit for a predetermined period, a normally latched spring controlled releasable means for operating said circuit closing means, and a shiftable spring controlled latch releasably engaging with said means when the circuit is open.

In testimony whereof, I affix my signature hereto.

ROBERT JARVIS SMOTHERS.
